UNITED STATES PATENT OFFICE.

THOMAS W. LANE, OF BOSTON, MASSACHUSETTS.

IMPROVEMENT IN FLUID-METERS.

Specification forming part of Letters Patent No. **173,024**, dated February 1, 1876; application filed October 26, 1875.

To all whom it may concern:

Be it known that I, THOMAS W. LANE, of Boston, in the county of Suffolk and State of Massachusetts, have invented Improved Fluid-Meters, of which the following is a specification:

This invention relates to water-meters of the class known as piston-meters; and consists in the combination, with the piston of a meter, of a valve-cylinder and a valve-piston adapted to operate substantially as hereinafter set forth.

The drawing, Figure 1, shows a longitudinal section of a piston-meter provided with this improvement, the section being taken through substantially the center of the cylinder, and the inlet and exhaust passages. Fig. 2 shows the pistons in their opposite positions; and Fig. 3, a view of the pistons removed from the cylinder.

The cylinder *a* is of suitable diameter and length, according to the size of the meter and the quantity of water or other fluid to be measured. The cylinder-heads *b* *b'* are confined by bolts or otherwise, passing through bolt-holes *c*, and in the cylinder is an inlet-passage, *d*, and an exhaust or outlet passage, *e*, (each shown as screw-threaded,) for the connection of the cylinder with a water-supplying pipe, and with a pipe to be supplied by water from the meter. The inner side of the cylinder is accurately, truly, and smoothly fitted to receive the piston *f*, which is a cylindrical shell, having fitted within it heads *g* *g'*, the connection being made by suitable screws. Fitted closely within this cylinder is a valve-cylinder, consisting of a shell, *h*, having inwardly-projecting dividing-walls *i* *i'*, and a central bearing, *j*, to sustain and guide the valve-piston *k*, the latter also fitting openings or bearings in the heads *g* of the piston *f*. Each cylinder-head has a depression, *l*, to receive the projecting hub at the end of the head of the piston. In the piston, opposite the inlet-passage, is an elongated longitudinal slot or passage, forming the inlet-port *m*, and opposite thereto, and in the other side of the cylinder opposite the exhaust-passage *e*, is an elongated longitudinal passage, forming an exhaust-port *n*, and at each end of the inlet and exhaust ports, and substantially at right angles thereto, and near the ends of the pis-

ton, are ports 1 2 3 4, of a proper width, and extending, in this instance, about the piston for, say, a distance of sixty degrees, more or less. The valve-cylinder has within it similar ports to those described in the piston, and substantially coincident therewith—viz., an inlet, *o*, and ports 5 6, and the outlet-port, *p*, which is sufficiently long and wide to extend over the exhaust *n*, and to the outer side of one of the ports 3 or 4. At the center of the valve-cylinder, and in its bearing-hub, are ports *r s*. The valve-piston *k* has ports at *t u v*, made by removing a portion of the periphery of the valve-piston. The ends of the valve-cylinder have recesses *w x*, forming water-chambers between the parts *i i'* of the valve-cylinder and the inner ends of the heads of the piston. Each moving part is fitted closely and smoothly to its outer or incasing part.

In Fig. 1 the piston has just completed its stroke in the direction of the arrow *x* at the side of the cylinder. The water or other fluid is yet passing into the inlet in the direction of the arrows through the ports *m o*, and 2. The cylinder, between its head *b'* and the piston-head *g'*, is full of water, and so is the space *w* between the valve-cylinder and head *g'* of the piston. Now, in this position, water passing through ports *r* and *u*, and acting against the head *g* and parts *i i'* of the valve-cylinder, will move the latter toward the head *g'* of the piston, and force the water in space *w* out through ports *v s*, into the chamber *a'*, and out through exhaust-ports *p n e*. During the movement of the piston in the direction of the arrow *x* the water between its head *g* and the cylinder-head *b* passes out through the port 3, into the chamber *a'*, and out through the exhaust. The valve-cylinder, under the action of the water between the end *g* of the piston and the parts *i i'*, as described, changes to the position shown in Fig. 2, the ports 2 and 3 are closed by portions of the shell *h* of the valve-cylinder, and ports 1 and 4 are opened, permitting the passage of the water, as shown by arrows in Fig. 2, the water between the heads *g'* and *b'* then passing through port 4 into chamber *a'*, and through the exhausts, and, water coming in through the inlet and ports *m o 5 1*, passes between the heads *g* and *b*, and forces the piston in a direction opposite

the arrow *x*, Fig. 1. During the movement of the valve-cylinder within the piston the valve-piston *k* moves in the direction of its arrow *7* just far enough to bring the shoulders *c' d'* into the end of bearing *j'*, in which *k* moves, and thereafter the valve-piston *k* moves with the piston without endwise movement in its bearing *j* until the end of the valve-piston meets the end *b'* of the cylinder. Then the valve-piston *k* is held at rest, while the piston continues to move toward *b'*, and the movement of the piston and valve-cylinder over the piston-valve opens the ports *t r* and *v s*, ready for the reception of the water between the head *g'* and part *i i'* to move the valve-cylinder, and to allow the water between the head *g* and part *i i'* to exhaust through ports *v s p n e* in the manner just above described, and the ports 2 and 3 are then opened, and the piston is ready to be moved in the direction of the arrow *x*, Fig. 1, by the action of the water through-port 2, the water in advance of the piston-head *g* passing out to the exhaust through ports *3 p n e*, and at the end of the stroke of the piston the parts will be again as shown in Fig. 1. The adjustable stops *e'* at the end of the cylinder act as stops, to change the position of the piston-valve sooner or later, to cause the change of motion of the piston sooner or later.

Instead of these stops the piston-valve may be shortened, the end of the piston may be closed, as shown in dotted lines, Fig. 1, and a pin or rod, *f'*, (shown in part in dotted lines, Fig. 1,) may project from the piston-valve through port *r o m*, and into a groove in the interior of the cylinder, (see dotted lines in Fig. 1,) and the pin, besides guiding the piston-valve, and preventing it from turning on its axis, will meet the shoulders or stops in the cylinder at the ends of the grooves, and change the piston-valve as desired. Stops may be ad-

justably fitted into this groove. At one end of the cylinder the stop *e'* is broken partially away, the part not shown being as its fellow *e*. Portions of the shell *f* of the piston may be cut away to lighten the piston, and make less surface for friction and wear, the shell of the valve-cylinder remaining whole, except as to the ports made therein for the passage of the water.

With this meter I propose to use a registering mechanism, substantially as shown and described in an application of J. Johnson, filed substantially concurrently with this, and the piston will be slotted at top, and be provided with a rack, to engage positively the registering mechanism.

The apparatus may be used as a motor for various purposes by connecting a piston-rod with the head of the piston, the rod extending through a stuffing-box in the head of the cylinder.

I claim—

1. The cylinder *a*, in combination with a reciprocating piston, *f*, a valve-cylinder, and a valve-piston, *k*, constructed and arranged one within the other, and adapted to operate, with relation to each other, substantially as described.

2. The piston, provided with ports, the valve-cylinder, provided with ports and center-bearing, and fitted within the piston, in combination with a valve-piston provided with ports, and adapted to be held, through contact with a stop on the cylinder, while the piston moves, substantially as described.

In testimony whereof I have signed my name to this specification in the presence of two subscribing witnesses.

THOMAS W. LANE.
